ROTARY FAN

Anwar A. Atalla, Torrington, Conn., assignor to The Torrington Manufacturing Company, Torrington, Conn., a corporation of Connecticut

Filed June 16, 1960, Ser. No. 60,989

Term of patent 14 years

(Cl. D26—7)

FIG. 1

FIG. 2

FIG. 3

FIG. 1 is a front view of a rotary fan showing my new design;

FIG. 2 is a side view thereof; and

FIG. 3 is a rear view thereof.

The characteristic feature of my design resides in the combination on the fan disclosed of the particular spider which is shaped as shown.

I claim:

The ornamental design for a rotary fan, as shown and described.
